UNITED STATES PATENT OFFICE.

ADOLF J. SCHNEIDER, OF BROOKLYN, NEW YORK.

SHOE.

1,345,407.

Specification of Letters Patent.

Patented July 6, 1920.

Application filed December 3, 1918. Serial No. 265,097.

To all whom it may concern:

Be it known that I, ADOLF J. SCHNEIDER, a citizen of the United States, residing at Brooklyn, in the county of Kings and State 5 of New York, have invented certain new and useful Improvements in Shoes; and I do hereby declare the following to be a full, clear, and exact description of the invention, such as will enable others skilled in the art 10 to which it appertains to make and use the same, reference being had to the accompanying drawings, and to characters of reference marked thereon, which form a part of this specification.

15 This invention has reference, generally, to improvements in shoes; and, the present invention relates more particularly to improvements in the class of shoes set forth in my former application for Letters-Patent, 20 filed May 16, 1918, Serial No. 235,016, in which the shoe is provided with the usual front opening connected with the upper of the shoe, the closing portions of the upper being provided with the usual eyelets or 25 other fasteners for the shoe-lacing, but in which the quarters of the shoe are also provided with an opening and overlapping members for closing said opening, means being provided in connection with said 30 members for securing said members in closed relation about the back and ankle of the foot so that the shoe can be quickly removed from about the foot, without disturbing the front closed arrangement of the 35 upper portions and of the lacing connected therewith.

The present invention, therefore, has for its principal object to provide in connection with a shoe of the character above stated, a 40 novel and improved shape of overlapping member to be used in connection with the opening at the rear of the shoe.

45 Other objects of the present invention not at this time more particularly enumerated will be clearly understood from the following detailed description of the present invention.

With the various objects of the present invention in view, the said invention consists, primarily, in the novel shoe herein-after set forth; and, the said invention consists, furthermore, in the novel arrangements and combinations of the various devices and parts, as well as in the details of the construction of said parts, all of which 55 will be more fully described in the follow-

ing specification and then finally embodied in the clauses of the claim which are appended to and which form an essential part of the said specification.

60 The said invention is clearly illustrated in the accompanying drawings, in which:—

Figure 1 illustrates in side elevation, a shoe made according to and embodying the principles of the present invention, the overlapping members upon the back of the shoe, as well as the front laced upper-portions all 65 being shown in their closed relations to the main body of the shoe.

Fig. 2 is a rear view of the shoe, showing 70 the overlapping members in their closed relation; and Fig. 3 is a similar view of the shoe, but the overlapping members thereof being represented in their separated or opened relation.

75 Fig. 4 is a side elevation of the rear end-portion of the shoe, with the overlapping members shown in their separated or opened relation; Fig. 5 is a longitudinal vertical section of said rear end-portion of the shoe, 80 said section being represented as taken on line 5—5 in said Fig. 3, looking in the direction of the arrow X; Fig. 6 is a transverse vertical section, taken on line 6—6 in said Fig. 1, looking toward the rear of the 85 shoe; and Fig. 7 is a detail face view of one of the overlapping members before being sewed in position to the respective quarter of the shoe.

90 Similar characters of reference are employed in all of the said above described views, to indicate corresponding parts.

Referring now to the several figures of the drawings, the reference-character 1 indicates a shoe of any desired form, style and 95 construction, the same being provided with the usual upper-members 2 having along their front edges an arrangement of eyelets, as 3, or other suitable lace-fasteners, for the reception of the lace 4 for closing 100 the front open portion of the shoe over the usual tongue 5. If desired, and as shown in Fig. 1 of the drawings, in addition to this usual arrangement of eyelets 3, auxiliary eyelets or perforations, as 6, may be 105 disposed along the upper marginal edge-portions 7 of the said upper-members 2 for the reception and securing therein of the respective ends of the lace 4 in any suitable manner, as will be evident, without the necessity of tying the lace-ends in the form 110 of a bow-knot.

The sole of the shoe is designated by the reference-character 8, said sole having the heel 9, and having secured thereto the vamp 10 which is formed with the usual heel-piece 11. As shown in the several figures of the drawings, the rear portions or quarters 12 and 13 of the respective uppers 2, also provide an opening at the rear-end of the shoe, one of said quarters, as 12, being 10 suitably extended and marginally formed in such a manner, so as to provide an inner closing member or flap, as 14, said closing member or flap, when the shoe is worn upon the foot, being disposed behind the other quarter 13, as indicated in the dotted outline in Fig. 2 of the drawings. The said quarter 13 is cut at its rear edge with the usual marginal straight and vertically disposed edge 15, and suitably secured to the 15 inner face-portion of the said quarter 13 is an overlapping closing member or flap 16, said flap 16 being of the general marginal configuration indicated in Figs. 4 and 7 of the drawings, and being secured in its operative position, by means of suitable stitching, in such a manner, so that the main body-portion 17 of said closing member or flap 16 will extend beyond the above-mentioned marginal edge 15 of the quarter 13, as shown 20 more particularly in Fig. 2 of the drawings, whereby when the shoe is worn upon the foot, the said extending portion of the flap 16 can be brought into its overlapping relation with the outer surface or face of the 25 quarter 12, as will be clearly understood from an inspection of said Fig. 2. That the said closing member or flap 16 is securely secured in its operative position with relation to the quarter 13, either upon or beneath the usual inner canvas or other suitable cloth lining of the shoe, (not here shown) the said flap 16 is provided with a suitably formed extension, 17, see Figs. 4 and 7, which is arranged against the inner 30 face of the rear end-portion of the vamp 10 or the heel-piece 11 and suitably secured thereto by stitching, or otherwise, the said flap 16 being also secured along the dotted line 18, see Fig. 7 and along the marginal edge 15 of the quarter 13 by proper stitching, or otherwise, to the said quarter 13.

Suitably inserted and secured between the heel 9 and the inner insert 19 of the shoe is the end-portion 21 of an upwardly extending tab 20 which extends upwardly and is doubled upon itself, as at 22, so as to form a loop or pull-portion 23, the downwardly extending portion 24 of said loop or pull-portion 23, being arranged against the inner face of the said member or flap 14 and the said quarter 12, substantially as shown in Figs. 3, 4, 5 and 6 of the drawings, and being secured in place by the stitching 25.

As shown, the said outer overlapping member or flap 16 has suitably secured upon

its outer face, and in the proper position, a reinforcing element 26 of leather, or the like, said reinforcing element being usually of a circular marginal configuration, and being made with an elongated hole or slot 70 27 in registration with a correspondingly disposed hole or slot 28 in said overlapping member or flap 16. Properly positioned upon the quarter 12 is a holding or retaining device, in the form of a stud, and of the general construction set forth in my said former application for Letters-Patent, Serial No. 235,016, which stud is adapted to be brought into engagement with the perforated or slotted portions of the said overlapping member 80 or flap 16 and said reinforcing member 26. This holding or retaining device consists, essentially of the main element or stud 29, with which the closing member or flap 16 is adapted to be brought into holding engagement, as shown in Figs. 1 and 2 of the drawings, and the reference-character 30 indicates the main back-plate of the device, said back-plate being separably connected with the said stud, in the manner set forth and 85 illustrated in my said former application, Serial No. 235,016, by means of the screw 31. As shown, the said back-plate 30 is eccentrically disposed with relation to the said stud 29, the purpose of this being that a 90 greater reinforcing member or element is provided upon the inner face of the quarter 12 at that point of the shoe-leather where the greatest strain is brought thereon, during the detachment of the reinforced part 100 of the closing member or flap 16 from the stud 29, as will be clearly evident from an inspection of the several figures of the drawings.

Furthermore, the arrangements and dispositions of the several parts of the holding or retaining device upon the quarter 12, and of the perforated or slotted portions of the flap 16 and its reinforcing member 26, are such that when the parts are brought into 110 their closed and retaining relation, the closing or retaining device or stud, and especially its eccentrically disposed back-plate, will be located at a position opposite the "hollow" at one side directly below the ankle 115 of the foot, so that in walking the parts will not become disconnected, nor cause any discomfort to the wearer of the shoe.

The construction, use and advantages of the invention will be readily understood 120 from the foregoing description of the present invention and from an inspection of the drawings which accompany the same, and any further description of the invention is therefore deemed unnecessary. It will also 125 be evident, that the invention is applicable to all styles of shoes worn by men, as well as women, without detracting from the appearance of the shoe or rendering it uncomfortable to the wearer.

I claim:—

A shoe having its quarters separated in the rear so as to provide an opening, one of said quarters having a rearwardly extending portion forming an integral part of said quarter and providing an inner closing flap, the other quarter having a straight marginal edge-portion, and an outer flap comprising a main body-portion and a flap-portion, said outer flap being secured by sewing along said straight marginal edge-portion diag-

nally across said outer flap on an imaginary line between the body-portion and the flap-portion of said outer flap, substantially as and for the purposes set forth.

In testimony, that I claim the invention 15 set forth above I have hereunto set my hand this 26th day of November, 1918.

ADOLF J. SCHNEIDER.
